UNITED STATES PATENT OFFICE.

HERMAN W. STEINMETZ, OF ROCHESTER, NEW YORK.

GAME APPARATUS.

Application filed January 18, 1922. Serial No. 530,205.

To all whom it may concern:

Be it known that I, HERMAN W. STEINMETZ, a citizen of the United States, residing at Rochester, in the county of Monroe and 5 State of New York, have invented certain new and useful Improvements in Game Apparatus; and I do hereby declare the following to be a full, clear, and exact description of the same, reference being had to the accompanying drawings, forming a part of this 10 specification, and to the reference numerals marked thereon.

My present invention relates to games and toys, and more particularly to games in 15 which a projectile is caused to traverse a runway set with hazards, and my invention has for its object to provide a game apparatus playable in imitation of a baseball game and in which improved means are employed for firing the projectile and for timing or retarding progress comparatively to 20 relative timing of long and short hits on a baseball field. To these and other ends the invention consists in certain improvements 25 and combinations of parts, all as will be hereinafter more fully described, the novel features being pointed out in the claims at the end of the specification.

In the drawings:

30 Figure 1 is a top plan view of a game apparatus constructed in accordance with and illustrating one embodiment of my invention;

35 Figure 2 is a longitudinal sectional view therethrough on the line 2—2 of Figure 1;

Figure 3 is a detail enlarged section on the line 3—3 of Figure 1;

Figure 4 is a perspective view of one of the counters;

40 Figure 5 is an enlarged horizontal section taken beneath the cover of the upper runway showing the timing devices;

Figure 6 is an enlarged transverse section taken through the lower end of the game 45 board and showing the projecting means;

Figure 7 is an enlarged vertical section through the projector;

Figure 8 is an enlarged vertical section through a timing device, and

50 Figure 9 is an enlarged fragmentary vertical section taken on the line 9—9 of Figure 5 looking in the direction of the arrow.

Similar reference numerals throughout the several views indicate the same parts.

55 My improved game board is preferably rectangular in form, as shown in Figure 1,

and enclosed by side rails or walls 1, a front rail 2 and a rear rail 3 in the vicinity of which is a suitable folding or other leg 4 adapted to maintain the game board at a slight incline. As best shown in Figures 1 and 2, the bottom of the board constitutes a lower runway 5 while above it and concealing it is an upper runway 6 shorter than the lower one but substantially parallel therewith. The upper runway is made to simulate a baseball field and diamond with the home plate 7 at the front and first, second and third bases as indicated at 8, 9 and 10. These bases and the home plate are in the form of sockets into which counters 11 representing the runners are adapted to be placed. The opposing players in the field are represented by pockets 12 in the playing positions of the pitcher, first, second and third baseman, shortstop and the three fielders. They open toward the rear or toward the incline and constitute hazards acting against the ball projectile 13 when rolled down the runway in the manner hereinafter described. If the ball avoids the hazard it rolls down to and lodges against a front rail 14 on the upper runway. The pockets 12 may be made of paper, fiber, thin metal or other material doubled over as shown in detail in Figure 3 and nailed down edgewise by a brad 15.

Mounted in the front rail 2 of the board is a projector or firing device for shooting the ball 13 up the lower runway 5. It consists in the present instance of a plunger 16 arranged in a cavity 17 in the front rail 2 of the board and provided with an intermediate shoulder 18 by means of which a spring 19 coiled about it within the cavity holds it normally retracted as to its front end, while its rear end 20 projects out from the other side of the rail 2, as shown in dotted lines in Figure 7. Pivoted to this side of the rail and near its bottom at 21 in a suitable bracket 22 is a hammer 23 actuated by a spring 24 coiled about its pivot. This spring 24 is superior to the spring 19 so that when the hammer is drawn down to the dotted line position of Figure 7 and allowed to snap back to the full line position it will project the plunger 16, as shown.

At one side of this firing device adjacent to the rail 2 is an incline 25. To fire the projectile 13 the player rolls the projectile 13 down this runway into the path of the plunger 16 while he holds the hammer 23 back and part of his skill in playing the

game is exhibited in releasing the hammer in time to cause the plunger to be projected just as the ball 13 reaches it to shoot the ball up the lower runway 5. Every time the 5 player misses accomplishing this a strike is called against him.

According to the proper timing or coordination of the movement just described the ball 13 travels straight up the lower runway 10 5 or at a tangent. If it reaches the top of said runway with any force it strikes a curved guide 26 located there and leading to the edge of the rear end of the upper runway 6. It travels up this guide and is deposited on the upper runway beneath a covering board 27 that conceals the upper or forward end of the board and the initial movement of the ball 13 when it first strikes the upper runway. Adjacent to the guide 15 26 on the under side of the board 27 is a yielding buffer 28 in the present form of a rubber or similar rib extending transversely above the end of the upper runway. This arrests the speed of the projectile as it enters 20 the upper runway.

The space between the upper runway and the cover board 27 is divided longitudinally into a plurality of channels by a number of parallel walls 29, the upper or forward ends 30 of which are tapered to a point to provide widened mouths for the channels into any one of which the ball may roll. These channels are marked respectively with the letters *a* to *k*. Some of these namely *a*, *b*, *d*, *f*, *h*, 35 *j* and *k* in the present instance offer no obstruction to the passage of the ball down them and onto the exposed baseball diamond of the lower portion of the upper runway. The others are provided with staggered pins 40 30 projecting from the sides of the wall members 29 and constituting tortuous passages through which the ball must find its way before reaching the diamond on which it can roll freely. These act as timing devices 45 for retarding the ball initially and they retard it more or less according to the number of pins that are present. For instance the ball would emerge from the channel *e* much sooner than from the channel *c*. Also 50 I prefer to make the mouths of the channels of the timing devices that provide for the greatest retarding action smaller than the others and in proportion to that action as shown for purposes of the game that will 55 later appear.

To prevent the ball from lodging against one of the pointed ends of the wall member 29, I provide ribs 31 leading to each of said points from the very edge of the upper runway 6. These may be formed by crimping transverse ribs in a strip of sheet metal 32 extending across the end of the runway.

At one side of the game board convenient to the player's hand I provide a leaf spring 65 33 having key hole slots 34 by means of

which it is detachably secured beneath the heads of screws 35 in a side rail of the board. This spring carries resiliently an elongated box 36 forming a channel in which a ball 37 may roll from end to end as the box is 70 tilted. The spring 33 normally holds the box tilted in one direction, as shown in Figure 8, but by depressing it with the finger against a stop 38 it may be caused to tilt in the opposite direction momentarily. As the ball rolls from one end to the other it encounters staggered pins 39 projecting from the sides of the box which retard its progress and cause it to measure an interval of time during each complete movement from end to 80 end.

The game is played in the following manner, although obvious modifications may be made to the rules herein prescribed:

The player that is having his inning fires 85 the projectile 13 with the device 16 and immediately depresses the timing device 36. If the projectile 13 is hit and deposited on the upper runway 6 and finds its way into one of the unobstructed channels, *a*, *b*, *d* etc. 90 it will roll down to the rail 14 before the timing ball 37 has completed its trip along the box 36 and the runner is out. If, however, it strikes the channel *e* it will be retarded sufficiently so that it will not strike the rail 14 until just after the timing ball 38 has completed one trip and the player has made one base. Similarly should it strike the runways *g*, *i* and *c* the runner will 95 make two, three or four bases respectively, the projectile 13 being sufficiently slowed by the home run channel 7 to permit of four trips of the timing ball 38, two in one direction and two in the other, it being understood that as long as the ball has not returned to the rail 14 the timing box 36 is 100 successively depressed and reversed so that the ball 38 will roll back and forth and mark off successive single base periods.

Of course the return of the ball or projectile 13 is not alone dependent upon the timing devices at the top of the board as the player's skill in striking it and giving it force has something to do with the speed and manner with which it enters any of the 115 timing channels and hence its progress therethrough, so that the game is a combination of skill and chance.

The masking of the timing devices at the upper end of the board by the cover board 27 adds to the excitement of the game as the luck of the projectile in entering a favorable or unfavorable channel is left a matter of suspense.

Of course if the ball rolls into one of the 125 opposing players' hazards 12 the player is out anyway, or the runner at least, and as at first described three unsuccessful attempts to hit the ball 13 and drive it onto the upper runway strikes out the batter. Where the 130

ball is hit but not sufficiently fair to reach the upper runway a foul is recorded.

I claim as my invention:

1. In a game apparatus, the combination 5 with a game board having upper and lower runways, the upper runway being provided with a plurality of separate channels, of a projectile adapted to initially traverse the lower runway, a curved guide connecting 10 the runways adapted to raise the projectile onto the upper runway and directed into one of the channels and a cover for the latter.

2. In a game apparatus, the combination 15 with a game board having upper and lower runways, the upper runway being divided into channels some of which are provided with hazards, of a projectile adapted to initially traverse the lower runway and 20 means for deflecting it and depositing it upon the upper runway.

3. In a game apparatus, the combination 25 with a runway and a projectile adapted to traverse the same, of a plurality of timing devices occupying a part of the runway having unequal retarding effect through any one of which the projectile is adapted to initially pass to impart to it a slow motion, the remainder of the runway being adapted 30 to an accelerated movement.

4. In a game apparatus, the combination 35 with a runway and a projectile adapted to traverse the same, of a plurality of timing devices occupying a part of the runway and having unequal retarding effect through any one of which the projectile is adapted to initially pass to impart to it a slow motion,

the remainder of the runway being adapted to an accelerated movement and means for masking said timing devices.

5. In a game apparatus, the combination 40 with a runway and a projectile adapted to traverse the same, of a plurality of timing devices occupying a part of the runway and having unequal retarding effect through any one of which the projectile is adapted to initially pass to impart to it a slow motion, the remainder of the runway being adapted to an accelerated movement, each such timing device embodying a channel having 45 staggered projections on its side walls against which the projectile is adapted to roll successively.

6. In a game apparatus, the combination 50 with a game board having upper and lower runways, of a projectile adapted to initially traverse the lower runway, means for deflecting it to the upper runway, and a plurality of parallel timing channels in the latter having different retarding effects and 55 through any one of which the projectile is adapted to roll.

7. In a game apparatus, the combination 60 with a game board having upper and lower runways, of a projectile adapted to initially traverse the lower runway, means for deflecting it to the upper runway, a plurality of concealed timing channels on the latter having different retarding effects and 65 through any one of which the projectile is adapted to roll, and a plurality of hazards on the upper runway.

HERMAN W. STEINMETZ.
